UNITED STATES PATENT OFFICE.

HENRY W. PLEISTER, OF WESTFIELD, NEW JERSEY, ASSIGNOR TO HENRY B. NEWHALL.

BOLT-ANCHOR.

1,267,902.

Specification of Letters Patent. Patented May 28, 1918.

Original application filed September 20, 1916, Serial No. 121,105. Divided and this application filed September 18, 1917. Serial No. 191,919.

To all whom it may concern:

Be it known that I, HENRY W. PLEISTER, a citizen of the United States, residing at Westfield, in the county of Union and State 5 of New Jersey, have invented certain new and useful Improvements in Bolt-Anchors, of which the following is a specification, taken in connection with the accompanying drawings.

10 This application is a division of my co-pending application, Ser. No. 121,105, filed Sept. 20, 1916.

My invention relates to bolt anchors and more particularly to a bolt anchor which 15 has a great holding capacity and yet one which will not crack a wall, a partition, a block of marble, stone or any other material in which it may be desired to use my bolt anchor.

20 The common form of bolt anchors are expanded by having the expanding member, the screw or bolt, moved down an inclined surface which extends approximately from one end to the other, and which reaches its 25 nearest approach to the axis of the bolt anchor at the end which is farthest embedded in the wall, block or other material. This causes the maximum expansion to be at the very end of the bolt anchor. This makes 30 it impossible to use the ordinary common form of expansion bolt in many locations.

My expansion bolt removes the point of maximum expansion from the end of the bolt anchor and insures a gradually lessening grip and wedging action from that point 35 to the end of the bolt anchor.

My invention further relates to certain 40 details of construction which will be described in the specification and pointed out in the claims.

I have shown in the accompanying drawings several illustrative embodiments of my invention but of course it is to be understood that my invention is not to be confined 45 simply to the forms illustrated. In these drawings the same reference numerals refer to similar parts.

Figure 1 is a side elevation partly in vertical section of a two part lag shield embodying my invention.

Fig. 2 is a longitudinal vertical section of the two part lag shield shown in Fig. 1 expanded and mounted in a comparatively thin wall or partition.

Fig. 3 is a vertical section of a one part 55 lag shield embodying my invention.

Fig. 4 is a vertical section of the one part lag shield of Fig. 3, mounted in a comparatively thin block of marble, stone or similar material, the work supported being also 60 shown in section.

In the illustrative embodiment of my invention illustrated in Figs. 1 and 2, 1 is a bolt anchor formed as a two part lag shield having complementary portions 2 and 3 and 65 lugs 4. The axial bore 5 tapers at 6 from near the large diameter at the entrance for the screw to a point intermediate its ends, as for example to the point 7, and from this point the axial bore has a reverse taper 9 70 to the large diameter at the inner end 8 of the anchor. In this form the point of greatest expansion will be approximately at the points 10, 10 and from those points to the end 8 of the shield the expanding strains and 75 stresses will recede or lessen.

It is well known that in thin masonry walls or thin partitions 11, which have the strength to support the work 12 of a given weight, that it is impossible to use bolt anchors satisfactorily because the wall or partition 11 is relatively so thin that their use will crack or destroy the surface 13 of the wall or partition thereby giving an unsightly appearance to the wall, if not actually requiring the services of a mason or plasterer 85 to touch it up or repair it.

By my invention I avoid the cracking, or marring or breaking of the wall or support 11 by removing the maximum strain and 90 wedging stresses from the points 14, 14, to a point removed from the end 8 of the bolt anchor and far enough away from the surface 13 so as to bring the point of maximum 95 expansion well within the body of the wall or partition 11.

To make the action more delicate and to insure that no possible excessive strain shall be caused to be exerted near the end 8 of the bolt anchor, I provide the bolt anchor 100 with one or more weakening portions 15. These weakening portions may be formed in any manner, preferably by casting deep valleys 16, 16 adjacent to the point 7, 7.

In the operation of my invention, Fig. 2 105 the hole 17 is formed in the wall or partition 11 leaving a comparatively thin portion 18. The bolt anchor 1 is then inserted and the

work 12, whatever its weight may be, will be snugly held to the face 20 of the wall or partition 11 by means of the lag screw 21 which will exert the maximum pressure at substantially the points 10, 10 well within the wall or partition and removed from the thin portion 18. From the points 10, 10 to the end 8 the gripping action of the bolt anchor will gradually lessen so that at the 10 very end 8 of the bolt anchor no such strains will be exerted which would cause the fracture, crumbling or marring of the face 13 of the wall or support.

When the lag screw 21 passes the point 7, 15 the weakening portion 15, 15 will permit the ends 22, 22 of the complementary sections 2 and 3 to move slightly with relation to the outer portion of the members 2 and 3 and tend to cause the two sides of the valleys 16, 16 to move apart or open, Fig. 2, should by any circumstances any considerable strain be exerted on the portions 22, 22 which might have a tendency to crack or injure the surface 13 of the wall or partition, 20 block or any other support.

I have also shown my invention, in Figs. 3 and 4, embodied in a one part lag shield 23. This lag shield is provided with an open throat 24, one or more lugs 25, 25 and open side 26, an inclined surface 27 reaching its nearest approach to the axis of the shield at the point 28 and from that point receding to the end 29 of the bolt anchor forming an oppositely inclined or flaring surface 30. This 30 one part bolt anchor I provide with a weakening portion 31 adjacent to the point 28. This weakening portion may be formed in various ways. Preferably I form it by casting a deep valley 32 which can be done at the same time that the article itself is cast. I, 40 preferably also provide the bolt anchor with screwthreads 33, 33 which are also preferably cast in the article.

In using this one part lag shield it is put 45 in the hole 34, in a thin wall or partition 35 Fig. 4, and a lag screw 36 holds the work 37 to the face 38 of the wall or partition 35 by engaging with the inclined surface 27 and the flaring surface 30, as well as directly 50 with the surface 39 of the hole 34 where it will cut or scrape female screwthreads or grooves into the body of the wall or partition 35.

The maximum expansion will be substantially at the point 40 and from that point will decrease or lessen to the end 29 of the shield. The weakening portion 31 insures that no possible excessive strain shall be caused to be exerted near the end 29 60 of the bolt anchor. When the lag screw 36 passes the point 28 the weakening portion 31 will permit the end portion 41 to move slightly with relation to the other portion of the lag shield and will tend to 65 cause the two sides of the valley 32

to move apart or open should by any circumstances any considerable strain be exerted upon the portion 41 which might have a tendency to crack or injure the surface 42 of the wall or partition or block or any other 70 support 35.

In all the figures of the drawing the inclined flaring surfaces, as well as the action of the weakening portion, are somewhat exaggerated for the purposes of clearer illustration. 75

It is apparent that different thicknesses of work 12 or 37 can be held by the same bolt anchor without the lag screw 21 or 26 binding before it has snugly secured the work to 80 the face of the wall or partition, block or other support.

Having thus described the invention in connection with different illustrative embodiments thereof, to the details of which I 85 do not desire to be limited, except as required by the scope of the appended claims, what is claimed as new and what is desired to secure by Letters Patent is set forth in the appended claims. 90

What I claim as my invention and desire to secure by Letters Patent is:—

1. An article of manufacture comprising a bolt anchor provided with a double inclined screw engaging surface and with 95 means to further insure that the maximum strains will not be transmitted to the support by the end of the bolt anchor.

2. In a bolt anchor the combination of an 100 expanding member having an inclined expanding surface reaching its nearest approach to the axis of the anchor between the ends of said anchor and from that point reversely inclined to form a flaring surface, said bolt anchor being provided with a 105 weakening portion, and an expanding member adapted to engage with both of said inclined and flaring surfaces.

3. In a bolt anchor the combination of a 110 two part bolt anchor having an axial bore diminishing in diameter to a point intermediate its ends and from that point increasing in diameter as it advances toward the other end of the anchor, said bolt anchor being provided with one or more weakening 115 portions, and an expanding member adapted to engage with both of said inclined and flaring surfaces.

4. In a bolt anchor the combination of a 120 bolt anchor member having an inner expanding surface inclined from near one end to a point intermediate the ends of the anchor member and from that point reversely inclined to form a flaring surface, said bolt anchor member being provided with a weakening portion, and an expanding member 125 adapted to engage with both the inclined and flaring surfaces.

5. In a lag shield the combination of a 130 double inclined screw-threaded surface to co-

operate directly with a lag screw, said lag shield being provided with a transverse weakening portion and a lag screw.

6. In a lag shield the combination of a double inclined screw-threaded surface to coöperate directly with a lag screw, said lag shield being provided with a transverse weakening portion adjacent to the nearest approach of the inclined surfaces to the axis 10 of the lag shield, and a lag screw.

7. In a lag shield the combination of a

body formed of comparatively rigid material, a double inclined screw engaging surface provided with screw threads, a weakening portion in the body of the lag shield, 15 and a lag screw coöperating directly with the screwthreads of the inclined surfaces.

HENRY W. PLEISTER.
